UNITED STATES PATENT OFFICE

BENGT OLSSON, OF ELTINGVILLE, NEW YORK, ASSIGNOR TO CHARLES J. O'NEILL, OF NEW YORK, N. Y.

OIL PUMPING APPARATUS

Application filed September 15, 1928. Serial No. 306,111.

My invention relates to an apparatus and method whereby viscous material like oil, molasses and heavy sludge may be pumped by a conventional force pump.

5 The device is specially adapted to be installed on board tankers and oil burning vessels and connected to their regular ballast pumps.

10 My invention has for its object to provide an upright vacuum chamber between the pump and the pump line proper. This upright vacuum chamber is at its middle connected to the pump line and at its lower part to the discharge pump and its upper part is 15 also connected to a vacuum creating device and by a non-return by-pass line to the pump intake proper.

The invention also provides a flexible hose which may be attached to the pipe line at any 20 convenient point and led into any of the oil tanks in the ship's bottom.

25 My invention further discloses a method whereby the nature of the viscous material is so changed that it becomes pumpable by a conventional force pump.

In the drawings:—

Figure 1 shows my preferred apparatus installed on board an oil burning vessel and connected to a conventional reciprocating 30 bilge or ballast pump which is shown provided with a strainer or mud box.

Figure 2 shows my device when used in connection with a centrifugal bilge pump on board the same ship.

35 Referring to the drawings in which like reference characters designate corresponding parts, 1 represents the oil burning vessel on which the reciprocating bilge pump 2, the bilge pump line 3, the mud box 4 and the discharge lines 5 and 6 are installed.

At a convenient place in the bilge line 3 the T-connection 7 is provided and the flexible hose 8 is attached to said connection.

40 The hose 8 is led into the double bottom of the vessel through the manhole 9 into the compartment 10 which is to be pumped and cleaned.

45 The upright vacuum chamber 11, preferably a pipe of six or eight inches diameter is

placed on top of the bilge line 3 and provided with a valve 12 at the bottom.

50 Approximately at the middle of said pipe chamber the inverted and contracted pipe bend 13 is provided through which outlet the bilge line 3 discharges into the pipe chamber 11.

The valve 14 is provided in the bilge line and the valve 15 is provided in the connection pipe 16.

55 On top of the chamber 11 a steam operated air exhauster 17 is mounted and connected to a convenient steam pipe 18 and exhaust line 19.

60 The by-pass line 20 connects the top of the pipe chamber 11 with the pump intake proper and the check valve 21 is inserted in this line.

65 When a centrifugal pump is used the arrangement is as shown in Figure 2.

70 The centrifugal pump 2' replaces the reciprocating pump and the mud box is dispensed with. At the discharge end of the centrifugal pump 2' a check valve 22 is provided. At the upper part of the pipe chamber 11 the vacuum relief valve 23 is installed.

75 The action of the apparatus is as follows:—

Either the overboard discharge 5 or the discharge line 6 is opened. The valve 14 is 80 closed and the valves 12 and 15 are opened.

The bilge pump and the steam operated air exhauster are started and the end of the hose 8 is dipped into the viscous material which is to be removed from the compartment 10.

85 It is to be noted that the end of the flexible hose is only partially dipped into the material so that air together with viscous material will enter into the transmission line during the operation.

90 With the intake end sealed in the manner described and shown on the drawings a piston wave of the viscous material is sucked up into and through the horizontal hose line sealing the same, whereupon a vacuum is being rapidly built up by the exhauster inside the bilge line 3 and the pipe chamber 11 which both have a relatively small displacement.

95 100 The transmission through the horizontal

bilge line is also distinctly a wave transmission until the wave reaches the vertical pipe 16 through which the wave will travel in form of a solid piston which is forcibly discharged into the pipe chamber 11 which in the meantime has been practically emptied by the bilge pump.

The piston slug will therefore forcibly impinge upon the liquid in the bottom of the pipe chamber and any air or water which was imprisoned in the viscous material in form of bubbles will be liberated by the impact and carried away respectively by the exhauster and the bilge pump.

15 It is to be noted that all the horizontal runs of hose and bilge line are always partially filled by a layer of the pumped material on the surface of which the wave transmission takes place.

20 It is also to be noted that the heavy oil sludge in a ship's bottom is an extremely viscous and stable air and water emulsion which cannot be pumped by a force pump. This emulsion is however effectively broken up 25 by the violent impact in the pipe chamber and the emulsion is here separated into its constituents which are removed as previously described.

In my preferred apparatus the breaking 30 down of the sludge emulsion takes place inside the pipe chamber 11 into which the piston slug is violently discharged against the liquid in the bottom of said chamber and it is therefore of the greatest importance to 35 provide means which will positively insure a perfect supply and discharge balance in said pipe chamber.

I therefore provide in said chamber an inverted inlet near the middle of the chamber 40 and a nonreturn by-pass line from the upper part thereof to the pump intake proper.

Should the slug discharge from the bilge line be in excess of the pump delivery the inverted inlet will be momentarily sealed and 45 the wave transmission through the bilge line will be stopped until the surplus is carried away.

The vacuum in the pipe chamber fluctuates 50 with each piston wave, but the check valve 21 insures a steady maximum vacuum in the by-pass line 20.

As the sealing of the inverted inlet takes place just when a slug has been discharged the vacuum in the pipe chamber is at this instant low while a higher vacuum prevails inside the by-pass line 20.

The surplus will therefore be drawn up in the pipe 20 from which it is withdrawn by 55 the bilge pump in the interim preceding the discharge of the next slug.

The pipe 20 acts therefore as a temporary repository of the momentary slug surplus.

This pipe also constitutes an escape of air 60 which may have been carried over from the

pipe chamber and prevent it from reaching the pump.

It is also to be noted that the arrangement prevents any liquid material from reaching the air exhauster especially as the relief valve 70 75 23 is set to open before the liquid level will reach either the by-pass line or the exhauster.

I do not wish to be understood as limiting myself to the specific details of construction as it is manifest that variations and modifications may be made in the adoption of the device to various conditions without departing from the spirit and scope of my invention.

An apparatus with which I have successfully pumped and cleaned the oil tanks of ocean going steamers through their regular bilge lines comprised a 6" pipe chamber provided with a 2" nonreturn by-pass. The pipe chamber was about 12' high.

The capacity of the air exhauster was less than one hundred cubic feet per minute and the vacuum in the pipe chamber fluctuated between 4 and 8 inches as indicated on the 80 85 vacuum gauge. A 3" flexible hose was used in feeding the bilge line.

I claim:

1. In a pumping apparatus an upright vacuum chamber, a pump suction connected to the lower part of said chamber and a direct nonreturn by-pass from said pump suction to the upper part of said chamber.

2. In a pumping apparatus an upright vacuum chamber, a pump suction connected to the lower part of said chamber, a substantially horizontal transmission line, an inverted inlet from said transmission line adapted to be sealed during pumping connected to said chamber and means for creating a vacuum connected to the upper part of said chamber.

3. In a pumping apparatus an upright vacuum chamber, a pump suction connected to the lower part of said chamber, a direct nonreturn by-pass connection from the pump suction to the upper part of said chamber and a substantially horizontal transmission line entering the chamber at a point lower than said by-pass connection.

4. The method of pumping a stable viscous emulsion characterized by creating a low vacuum in a receptacle admitting air at the suction end of the transmission line to thereby accelerate a slug wave horizontally, instantaneously arresting the slug wave in said receptacle and withdrawing the material from said receptacle by a force pump.

5. In a pumping device, in combination, a substantially horizontal transmission line for liquid material, an upright vacuum chamber, said transmission line being connected to the central part of said chamber, said chamber extending upwards and above the transmission line, a discharge at the bottom of said chamber and a nonreturn vacuum by pass

from said discharge to the top of the upright vacuum chamber.

6. In a pumping device, in combination, a substantially horizontal transmission line for liquid material, an upright vacuum chamber, said transmission line being connected to the central part of said chamber, said chamber extending upwards and above the transmission line, a discharge at the bottom of said chamber, a pump connected to said discharge, a nonreturn vacuum by pass from said discharge to the top of the upright vacuum chamber and strainer means interposed between the vacuum chamber and the nonreturn by-pass.

7. A device adapted for the attachment to a reciprocating bilge pump on board maritime vessels comprising in combination a flexible hose connected to the bilge suction line and adapted to be led into the double bottom compartments of the vessel, an upright pipe superimposed on top of the bilge line at the suction end of the strainer or mud box, a by-pass from the bilge suction line to the middle part of the upright pipe, a vacuum suction from the upper part of said pipe and a non-return by-pass from the pump intake to the upper part of said upright pipe.

8. In a pumping device for liquid material a vacuum chamber, a pump suction from the chamber, means for creating a fluctuating vacuum in the vacuum chamber, an additional repository connected to the pump suction and extending upwards and a nonreturn connection leading from the upper part of the additional repository to the upper part of the chamber.

9. In a pumping device for liquid material, a vacuum chamber, a pump suction from the chamber, means for creating a fluctuating vacuum in the vacuum chamber, an additional repository connected to the pump suction and extending upwards, a nonreturn connection leading from the upper part of the additional repository to the upper part of the chamber and means preventing the flooding of said chamber.
